UNITED STATES PATENT OFFICE.

EDWIN L. THOMAS, OF BUFFALO, NEW YORK.

GAS-ENGINE.

1,325,765.

Specification of Letters Patent. Patented Dec. 23, 1919.

Application filed May 29, 1915. Serial No. 31,167.

To all whom it may concern:

Be it known that I, EDWIN L. THOMAS, a citizen of the United States, residing at Buffalo, in the county of Erie and State of New York, have invented new and useful 5 Improvements in Gas-Engines, of which the following is a specification.

This invention relates to a multiple cylinder gas engine, and more particularly to 10 an engine of this character commonly known as V-shaped motors.

In engines of this type as heretofore constructed the valves and their operating mechanism are usually so arranged that the 15 same are difficult to reach for the purpose of inspecting, adjusting or repairing the same and are so organized that the engine is difficult to cool and many parts are exposed and detract from the appearance of the engine. 20

The object of this invention is the production of V-shaped multiple cylinder engines in which the valves and their operating mechanism are so arranged that these parts 25 are conveniently and readily accessible when inspection, adjustment or repairs are necessary, which permits of efficiently cooling the cylinders and in which the valve mechanism is concealed so as to improve the appearance of the engine. 30

In the accompanying drawings:

Figure 1 is a vertical transverse section of a multiple cylinder gas engine embodying my invention, the section being taken 35 through a pair of opposing cylinders and their companion intake valves and associated parts. Fig. 2 is a fragmentary vertical transverse section of the same taken through the exhaust valves of a pair of cylinders and associated parts. Fig. 3 is an 40 oblique longitudinal section taken on line 3—3, Fig. 1. Fig. 4 is a vertical longitudinal section taken on line 4—4, Fig. 1. Fig. 5 is a fragmentary horizontal section taken 45 on line 5—5, Fig. 1.

Similar characters of reference indicate corresponding parts throughout the several views.

1 represents the crank case of the engine. 50 which is provided at its opposite ends with longitudinal bearings 2, 3 and 4 is the crank shaft arranged lengthwise in the crank case and journaled in said bearings.

55 5, 6 represent a plurality of pairs of opposing power or working cylinders which are arranged at an angle relatively to each

other and connected at their inner or front ends with opposite sides of the crank case so that the axes of these cylinders forming a pair converge downwardly toward the 60 crank shaft and intersect the axis of the latter. 7, 8 represent pairs of pistons which reciprocate lengthwise respectively in the cylinders 5, 6 and each pair of pistons being connected by pairs of pitmen or connecting rods 9, 10 with one of a number of cranks 11 on the crank shaft. The number of pairs of cylinders, pistons and connecting rods and the number of cranks may be varied according to the output of power desired but in the drawings, as an example, 65 three pairs of cylinders, pistons and rods are shown together with three cranks and the latter are arranged on different radial lines relatively to the crank shaft, so that 70 the operations of drawing in charges of fresh fuel, compressing the same, exploding the charges and exhausting the same relatively to the several cylinders, may be effected successively and in proper sequence 75 to cause the engine to run smoothly and distribute the strains evenly in the usual and well known manner practised in this type of engine.

12, 13 represent two valve chests arranged 80 lengthwise on opposite sides of the longitudinal center or crank shaft and each chest connecting with the upper parts of the outer ends of the cylinders on one side of the engine. These two valves chests are connected 85 by a horizontal cross piece or truss 14 which is separated on its underside from the cylinders and crank case by an intervening space or passage 15 through which air may circulate freely for assisting in cooling the engine 90 when the same is in operation. This cross piece, the valve chests, the several pairs of cylinders and the upper part 16 of the crank case are preferably formed integrally by casting the same in one piece, while the 95 lower section 17 of the crank case is detachably connected by bolts 18, or otherwise to the upper section 16, whereby a very strong 100 and durable construction is produced.

105 Each of the valve chests is provided with a fuel supply manifold or intake 19 which opens by means of a fuel inlet port 20 into a valve chamber 21 forming an upward extension of the upper end of each cylinder on the respective side of the engine, and also 110 with an exhaust manifold 22 which opens by means of an outlet or exhaust port 23 into

one of the valve chambers, so that each of the latter has an inlet port and an outlet port, as shown in Figs. 1, 2, 4 and 5. The fuel inlet and exhaust outlet ports 5 of each valve chamber are controlled by a pair of inlet and outlet valves 24, 25 preferably of disk form arranged in the respective valve chamber and movable transversely outward to open said ports and inwardly for closing the same. These valves are arranged on the outer ends of the front or outer sections 26, 27 of two horizontal valve stems or rods which stem sections are arranged parallel and reciprocate in horizontal guideways 28, 29 arranged on the adjacent valve chest, as shown in Figs. 1, 2 and 5. The inner or rear sections 30, 31 of the stems of the inlet and exhaust valves are adjustably connected with the respective 10 outer valve stem sections and guided in sleeves 32, 33 mounted in the standard 34 rising from the adjacent part of the cross piece or truss. These valve stems are moved inwardly for closing the valves which they 15 carry by means of outer or front springs 35 each of which surrounds an outer valve stem section and bears at its outer end against the adjacent valve chest while its inner end bears against a collar or shoulder 20 36 on the respective outer valve stem section, and inner or rear springs 37 each of which surrounds one of the inner valve stem sections and bears at its outer end against a shoulder on the adjacent guide sleeve while 25 its inner end bears against a head 38 on the inner end of the respective inner valve stem section, as shown in Figs. 1, 2, and 5. On the outer sides of the valve chests the same are provided with openings in line with the 30 valves through which the latter and their stems are moved when mounting or unmounting the same and which are normally closed by screw caps or plugs 39, 40 or the like. 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930

means for rotating the same are so timed that during the forward suction stroke of each piston the companion fuel valve will be opened to permit a charge of fuel to be drawn into the respective cylinder, during the following backward stroke this fuel valve is closed so that the charge of fuel is compressed, the next forward stroke of the piston is produced by the pressure of the exploding charge which is ignited by a spark plug 48 or the like and whereby the power is developed, and during the succeeding return stroke the exhaust or outlet valve is opened to permit the spent gases or products of combustion to escape, this operation being like that of the well known type of gas engines working on the four-stroke cycle principle.

Above the valve shaft and the inner ends of the valve stems and associated part is arranged a cover 49 which is detachably secured at its edges by screws 50 to the valve chests and cross piece.

When the valve operating mechanism is thus covered a neat appearance of the engine is presented inasmuch as all its working parts are by this means concealed from view.

Whenever it is desired to inspect, adjust, or repair the valve operating mechanism it is only necessary to remove the cover 49 whereby all parts of this mechanism are accessible and within convenient reach so that any attention which this mechanism requires may be easily and readily given to the same.

This advantage is due to the fact that valve stems are raised at an angle to the working cylinders and arranged in the upper part of the space between the converging cylinders, instead of being parallel with these cylinders and arranged in the lower part of this space. Although the precise arrangement of the valve stems relatively to the working cylinders may be varied and still secure this advantage, it is preferable to so arrange the cylinders of a pair that they form two sides of a triangle and to so arrange the stems of the valve mechanism associated therewith that they form the third side of this triangle. This arrangement not only renders the valve operating mechanism easy of access, but the same owing to the triangular relation of the working cylinders, cross-piece and the parts movably mounted thereon produces an exceedingly strong construction which is capable of withstanding great strains, thereby rendering the same particularly desirable where a strong, light, powerful engine is required.

I claim as my invention:

A multiple cylinder gas engine comprising a crank shaft, two power cylinders provided at their outer ends with fuel intakes and exhaust outlets and having their axes converging toward said crank shaft, intake

and exhaust valves for controlling the intakes and exhausts of said cylinders and having reciprocating stems which project toward each other and are arranged at an angle to their respective cylinders, a valve shaft arranged between said valves and parallel with said crank shaft and having cams operating on the inner ends of said valve stems, an upper base section connecting the lower ends of said cylinders, and guides for said valve stems, said cylinders

forming two sides and said valve stems the third side of a triangle, and the junction of the center line of said valve stems and the axes of said cylinders being arranged beyond the outer ends of said cylinders and said valve stems and cam shaft being arranged in the same plane, said cylinders, fuel intakes, exhaust outlets, valve guides and upper base section being formed integrally of a single casting.

EDWIN L. THOMAS.
